UNITED STATES PATENT OFFICE.

BERTHOLD JAHN AND ERNEST E. KAHL, OF NEW BRITAIN, CONNECTICUT, ASSIGNEES
TO THE B. JAHN MANUFACTURING COMPANY, OF NEW BRITAIN, CONNECTICUT,
A CORPORATION.

STAPLE-BINDER.

1,387,268.

Specification of Letters Patent.

Patented Aug. 9, 1921.

Application filed June 19, 1919. Serial No. 305,431.

To all whom it may concern:

Be it known that we, BERTHOLD JAHN and ERNEST EMIL KAHL, citizens of the United States, residing at New Britain, in the county 5 of Hartford and State of Connecticut, have invented certain new and useful Improvements in Staple-Binders, of which the following is a specification.

Our invention relates to improvements in 10 staple binders, and has particular reference to improvements in the staple binder shown and described in our application filed November 26, 1916, Serial No. 133,357, and the object of our improvement is to incorporate 15 in a staple binder of the form mentioned means for positively holding the end portion of the staple strip that is adjacent the plunger and the coöperating cutting edge of the die portion of the die member in close 20 association with the said die member on which it is mounted when the staple binder is in use and thereby preventing the staple strip from being accidentally displaced from the proper position for being operated upon 25 by the plunger, particularly as by contact with the plunger in its upward return movement.

In the accompanying drawing:

Figure 1 is a side elevation of our improved staple binder.

Fig. 2 is a plan view of the same.

Fig. 3 is a side elevation of the left side plate of the frame, as viewed from the inside.

Fig. 4 is a fragmentary side elevation of the right side plate as viewed from the inside.

Fig. 5 is a sectional view on the line 5—5 of Fig. 2, on an enlarged scale.

Fig. 6 is a fragmentary view on a still further enlarged scale of certain parts shown in Fig. 5.

Fig. 7 is a sectional view on the line 7—7 of Fig. 6.

Fig. 8 is a fragmentary sectional view on the line 8—8 of Fig. 6.

Fig. 9 is a side elevation, on the same scale as Fig. 1, of a modified form of structure.

Fig. 10 is an inside view of the left side plate of the structure shown in Fig. 9.

Fig. 11 is a fragmentary sectional view, of the modified form corresponding gener-

ally to Fig. 5, and on the same scale as the said Fig. 5.

Fig. 12 is an enlarged view of some of the parts shown in Fig. 11.

Fig. 13 is a sectional view on the line 13—13 of Fig. 12.

Fig. 14 is a sectional view on the line 14—14 of Fig. 11.

The parts of our improved staple binder that are common with the staple binder shown and described in the application mentioned comprise a base 10 having an anvil 11 at one end and a pair of arms 12 at the other end, in spaced relation, for pivotally connecting with a swinging member and having holes for the pivotal pin 13.

The said swinging member comprises a composite structure, composed of the die member 15 that is opposed to the base 10 and a pair of side frame plates 14 extending upwardly from the said die member 15 and forming therewith a housing for inclosing certain parts of the operating mechanism.

The plunger 16 is operatively supported in the front part of the frame structure, being engaged with ways 17 that are provided on the side plates 14, and is normally held in elevated position by means of the spring 18.

The plunger 16 has on the inner side, within the housing formed by the side plates 14 a web or fin structure 19 the upper portion 20 of which coöperates with opposed flanges 21 on the side plates 14 for limiting the upward movement of the plunger responsive to the action of the spring 18, and the lower portion 22 of which operates as a cam device for coöperating with the swinging dog 23.

The side plates 14 are formed of sheet material, and the flanges 21 are in the form of inwardly turned portions of the said sheet material.

The lower end of the plunger 16 has on the inner side a cutting edge 24 for coöperating with the opposed cutting edge 25 on the end of the die member 15 for severing the individual staples 26 from the staple strip when the plunger is forced downwardly, the said lower end of the plunger as the movement of the plunger is continued downwardly forcing the severed staple downwardly so that the legs or prongs of the staple will be

pushed through the papers laying over the anvil 11 and finally clenching the staple in cooperation with the anvil 11.

The operation described is effected by means of a blow on the handle 27 on the top of the plunger 16 and when released the spring 18 raises the plunger 16.

During such return movement of the plunger 16 the staple strip is moved forwardly so as to bring the end staple 26 of the staple strip into position in the path of the plunger 16 suitably to be operated upon and the mechanism for effecting such forward movement or feeding of the staple strip comprises a holding pawl 28 that operates to prevent retrograde movement of the staple strip and the feeding pawl 29 for feeding the staple strip and that is operatively supported from the swinging dog 23. The holding pawl 28 is pivotally supported from the side frame member 14 by means of the pivotal pin 30 and is provided with a positioning spring 31.

The feeding pawl 29 is operatively connected to the swinging dog 23 by means of the pivotal pin 32 and the positioning spring 33 and the said swinging dog 23 is pivotally supported from the side frame members 14 by means of the pivotal pin 34.

30 A plurality of positioning pins 35 are provided for positioning the die member 15 and the side frame members or side plates 14 relatively one to the other and these parts are held together by means of a plurality of screws 36.

The upper portion 37 of the die member 15 is reduced in width relatively to the lower portion so as to provide a pair of channels 38, one on each side, for the legs of the staples 26, in the usual manner, the middle portion of the staples 26 and the connecting backbone of the staple strip resting on the upper face of the said upper reduced portion 37 of the die member 15 during the severing operation.

During the return movement of the plunger after having severed and clenched a staple the inner face of the plunger is opposed to the freshly cut edge of the staple strip and is extremely close thereto in all cases and these parts may contact one with the other in case of a slight displacement of the staple strip in the direction toward the plunger. Such contacting is liable to result in displacing the staple strip so that it would be misplaced in position on the die member 15 for proper cooperation with the feeding devices so that the final result in some cases would be to clog the machine.

60 We find that the difficulty outlined may be overcome by providing means for positively preventing lifting the staple strip appreciably from the proper operating position on the upper reduced portion 37 of the die member 15 on which it is supported and do

this in the following manner:—On the inner faces of the side plates 14 we provide opposed inwardly directed ribs 39 of appreciable length and parallel with the upper face of the die member 15, on the portions of the side plates 14 that are adjacent the cutting edges 24 and 25, so as to overhang the space of the side channels 38 for the legs of the staples 26 and spaced above the upper surface 40 of the die member 15 by a space that suffices to permit of free movement of the staple strip in the longitudinal direction for proper operation and at the same time prevents appreciable lifting movement of the staple strip upwardly from the said upper surface 40.

70 As a detail, we prefer to form the inwardly directed overhanging rib 39 by means of an indentation on the outer face of the side plates 14, which plates, as described, are made of sheet material.

75 Thus the two ribs 39 coöperate with the upper face 40 of the reduced portion 37 of the die member 15 to provide a way for the upper portions of the staples 26 and the staple strip generally which permits of free movement in the proper direction for co-operation with the plunger and the feeding mechanism and prevents displacement such as would interfere with proper operation of the said plunger and feeding mechanism.

80 In the construction described it will be noted that the forward end 41 of the rib 39 is opposed to the inner face 42 of the plunger 16, so that by properly positioning the said rib longitudinally the said forward end 41 will serve as a guide for the plunger. This is the arrangement, with certain additional features pertaining to details that 90 is followed in the structure shown in Fig. 9 and the following figures.

85 In both forms of structure the guide portion of the frame is composed of two opposed and inwardly directed ribs 43 that are integral with the side frames 14.

90 In the structure first described the cross section of the plunger 16, shown in Fig. 8, is of I-beam form, comprising opposed grooves 44 for the ribs 43. By providing 95 guide means coöperating with the inner face 42 of the plunger it will be noted that a T-shape for the cross section of the plunger 16^a, as shown in Fig. 13 suffices. Thus the forward end 41, as described, serves as the 100 guide for the plunger 16^a for the lower part thereof.

105 Guide means for the upper portion of the plunger 16^a are provided by the forward end portions 45 of the inwardly turned flanges 21 of the frame plates 14 already 115 mentioned and which are also opposed to the inner face 42 of the plunger 16^a.

110 Thus the T-shaped cross section of the plunger 16^a comprises a stem portion 46 that extends outwardly through the space 120

between the inwardly turned flanges or ribs 43 and a pair of laterally directed flanges or ribs 47 that are positioned between the inner faces of the ribs 43 and the guide means 5 already described for coöperating with the inner face 42 of the plunger 16, comprising the end 41 of the rib 39 for the lower portion and the ends 45 of the ribs or flanges 21 for the upper portion.

10 Additional ribs for coöperating with the plunger may be provided for extending the guide structure for coöperating with the inner face 42 of the plunger, such as the vertical rib 48 adjacent the upper guide 45 15 and the rib 49 in line therewith and adjacent the lower guide 41. The last named rib 49 may emerge with the rib 39 so as to form therewith a combined rib of right angled form, as shown, and which is formed by 20 indenting the sheet material of the side frame plates 14.

The ribs 48, one on each side, are formed by indenting the material of the plates 14.

We claim as our invention:—

25 1. A staple binder comprising a die having a cutting edge at one end and having a reduced portion along one face for slidably supporting a staple strip, a housing connected with the said die inclosing the said reduced portion, feeding mechanism for feeding the said strip along the said reduced portion contained in the said housing, a plunger operatively supported by the said housing, having a cutting edge for coöperat-

ing with the said cutting edge on the die; 35 and also having means for operating the said feeding mechanism, the said housing comprising a pair of side plates positioned on opposite sides of the said reduced portion, and inwardly directed ribs being provided on the inner faces of the said side plates for overhanging the said reduced portion, suitably to engage with the upper face of the said staple strip.

2. A staple binder as described in claim 45 1, the said side plates being made of sheet material, and the said inwardly directed ribs being formed by indentation of the said sheet material.

3. In combination in a staple binder, a 50 frame, a die incorporated with the said frame, a plunger supported in the said frame for coöperating with the said die, and having side flanges for serving as guides, side plates on the said frame and positioned one 55 on each side of and opposed to the edge portions of the said flanges, a guide flange in the form of an inwardly turned edge being provided on each of the said side plates for coöperating with the outer faces 60 of the said side flanges on the plunger, and guide means for coöperating with the inner faces of the said side flanges, the said guide means being in the form of indented ribs in the material of the said side plates.

BERTHOLD JAHN,
ERNEST E. KAHL.
